FLUID SYSTEM

Paul R. Loughin, Westfield, N. J., assignor to The Babcock & Wilcox Company, Jersey City, N. J., a corporation of New Jersey

Application August 22, 1942, Serial No. 455,690

6 Claims. (Cl. 122—235)

This invention relates to heat exchange installations, and the invention may be regarded as exemplified in superheaters or reheaters utilized, in conjunction with (or as parts of) steam generators.

The invention involves an improvement in an installation which includes a header having a fluid inlet at each end and a row of header outlets along the header and between the inlets. In this type of construction, the invention assures the outlet tubes of a supply of fluid which is a combination or mixture of the fluids originating at the widely separated header inlets. When the header is supplied with superheated steam through the inlets the supply of steam from one inlet may be conditioned differently from the steam supplied from the other inlet, and this condition may be one of temperature or some other condition relating to the quality of the steam supplied. Under these circumstances the invention not only distributes the supply of steam from each inlet along the length of the header or over the range of the zone of the inlets, but it also interposes a diffusion chamber in which the fluids from the different inlets must be mixed before entering the outlet tubes. Thus, when the varying condition of the steam from the two sources is one of temperature, the invention will operate to cause the steam at the outlets to be of a temperature which is substantially an average temperature of the varying inlet temperatures.

Superheaters or reheaters involve a plurality of tubes conducting steam through a zone in which the tubes are subjected to high temperatures. From the standpoints of uniform heating and tube protection, it is important that the temperature of the steam entering the tubes be uniform and this is particularly true of wall tube superheaters of the radiant type. It is an object of the invention to attain this result with such reliability that tube overheating will not occur even when the heater tubes have their inlet ends communicating with an inlet chamber receiving steam from a plurality of other heater sections which may so operate that each supplies steam to the inlet chamber at a temperature differing considerably from the steam supplied by the others.

A preferred embodiment of the invention will be referred to in detail in the following description, and other objects of the invention will appear as the description proceeds. The description refers to the accompanying drawings in which:

Fig. 1 is a vertical section of a steam generator; 55

Fig. 2 is a horizontal section of the reheat inlet header having conduits associated with its ends for the delivery of steam thereto from other reheat sections;

5 Fig. 3 is a transverse section on the plane indicated by the line 3—3 of Fig. 2, looking in the direction of the arrows;

Fig. 4 is a transverse vertical section of the Fig. 2 inlet header taken on the line 4—4 of Fig. 2;

Fig. 5 is a diagrammatic view indicating the relationships of the side wall reheat sections to the remaining section of the reheat;

Fig. 6 is an enlarged horizontal section of one end of the reheat inlet header showing the details of construction;

Fig. 7 is a transverse vertical section taken on the line 7—7 of Fig. 6; and

Fig. 8 is a detail view illustrating means for maintaining one of the steam distributors of the reheat inlet header in operative position. This view is taken on a vertical plane indicated by the line 8—8 of Fig. 6, looking in the direction of the arrows.

The drawings illustrate the reheat as an integral part of the high capacity steam generator operating at pressures in excess of 2400 lbs. per sq. in. The steam generator includes a furnace 10 from the lower part of which gases flow into an open up-pass 12. From the upper end of the pass 12, the gases flow into a down-pass 14, and from the lower end of this second open pass the gases turn and flow upwardly through a convection section 16 including a superheater section 18 and an economizer 20.

The walls of the furnace 10 include steam generating tubes connected at their upper ends with the steam and water drum 22, and at their lower ends with the water drum or header 24. The fluid circuit is completed by suitable large diameter downcomers (not shown), connecting the water space of the drum 22 with the drum or header 24.

Some of the steam generating tubes have parts aligned to define the furnace wall 30 which separates the first open-pass 12 from the furnace, and other steam generating tubes define the wall 32 separating the two open-passes 12 and 14.

The rear wall of the second open-pass 14 is defined by the vertical parts of reheat tubes 34 which have their inlet ends connected to the reheat inlet header 40. Lower parts of these tubes are more widely spaced, and are arranged to form screen 44 extending across the inlet of the convection section.

The furnace 10 is fired at high temperatures by the pulverized fuel burner 50 and incombustible residues of the fuel flow in molten form through the slag outlet 52 at the base of the furnace.

High rates of heat absorption are obtained in the walls of the open passes 12 and 14 by presenting the bare metal of their wall tubes to the furnace gases in these passes, such high rates of heat absorption effecting extensive cooling of the slag or ash particles which may be carried in suspension in the furnace gases. Thus separation of the suspended solids is promoted and the solids are so conditioned that there is a minimum of their accumulation upon the spaced tubes of the convection section. They are cooled in the open-passes to temperatures below temperatures at which the solids adhere to the tubes.

From the steam and water drum 22 steam passes through the conduits 54 to a superheater inlet header 56, and superheater tubes 58 extend downwardly from the latter to a position below the economizer 20 where they continue in the form of return bend coils which extend across the path of the furnace gases in the convection section. In Fig. 1, three successive sets 60-62 of such return bend coils are shown. From the last of these, the superheater tubes continue to the intermediate superheater header 64.

From the header 64 steam passes through the upwardly extending conduit 66 to a transverse header 68 to which superheater tubes 70 are connected. These tubes are arranged in rows in the form of platens which extend through the roof 12 and thence downwardly through the second open-pass 14 at spaced positions across that pass. At their lower ends these tubes are bent to the right so as to pass through the inclined wall 74 at the base of the installation. Beyond this wall the tubes are joined to a superheater outlet header 76 connected to a steam turbine. After use in the steam turbine the steam passes through the reheat conduit 80 directly connected with a side wall inlet header 82. From this header, reheat tubes extend upwardly at such positions that they form a side wall of each of the open-passes 12 and 14. The upper ends of these tubes are connected to a header 86 from which the steam passes to reheat inlet header 40. It should be understood that at the opposite side of the steam generator there are headers similar to 82 and 86, and that these headers are connected by similar reheat tubes forming the other side walls of the open-passes 12 and 14.

The arrangement of the side wall reheat sections and the remaining reheat section is diagrammatically indicated in Fig. 5 in which the reheat side wall tubes 92 are shown as connecting the inlet header 90 with the intermediate reheat header 94. This figure indicates the flow of steam through the two separate reheat side wall sections to the end portions of the reheat inlet header 40. The tubes 34 of the last section of the reheat are connected at their lower ends to a reheat outlet header 100, from which the reheated steam passes through a conduit 102 to a point of use.

If, during the operation of the steam generator, combustion conditions result in deposits of slag or ash particles to an extent on one of the reheat sidewall sections, greater than that on the other, steam flowing into one end of the reheat inlet header 40 may consequently be at a temperature higher than the temperature of the steam flowing into the other end of that header. If this condition should arise, there would be non-

uniformity of steam heating by the tubes 34 of the last reheat section. Such lack of uniformity is apt, not only to result in loss of overall efficiency and overheating of some of the reheat tubes, but it is also apt to cause damage to a turbine utilizing the reheated steam. These undesirable contingencies are prevented by means within the reheat inlet header 40 for separately and uniformly distributing steam from each of the side wall reheat sections throughout the effective length of the header 40. The illustrative means, shown in detail in Figs. 2, 3, 4, 6, 7, and 8, not only results in uniform distribution of the steam from the separate side wall reheat sections, but it also causes the steam supply from these two separate sources to be thoroughly mixed within the reheat header 40, before the steam passes from that header into any of the reheat tubes 32.

As indicated in Figs. 2, 3, and 4 of the drawings, the header 40, between the inlets 86 and 94, is provided with oppositely tapering distributors 104 and 106 which are spaced inwardly of the interior walls of the header to provide an annular steam mixing chamber 108. Each of these distributors has a flat wall joined by a curved wall formed to the arc of a circle. For instance, in the drawings, the distributor 104 is shown as having a flat wall 110 and a curved wall 112, while the distributor 106 has a flat wall 114 and a curved wall 116, the distributors being complementary to form an overall body of cylindrical contour, as indicated in Figs. 3 and 4.

The inlet or larger end of the distributor 104 receives steam from the header 86 as indicated in Figs. 2 and 5, and this end of the distributor has a plate 120 fixed thereto. This plate fits within an opening in the header 40 and serves to support the distributor 104 as well as to provide a closure for one end of the annular mixing chamber 108.

At the opposite end of the header 40 the distributor 106 is provided with a similar diaphragm plate 122 closing off the other end of the annular mixing chamber 108 and causing the steam in the header 94 to flow through the distributor 106. Each distributor is also fitted with a plurality of longitudinally spaced groups of circumferentially distributed spacers 130-137, as indicated in Figs. 3 and 4 of the drawings. These spacers serve to center the distributors within the header 40 and provide a uniform mixing chamber. As clearly indicated in Figs. 6, 7, and 8 of the drawings, the distributor 104 is held in place longitudinally of the header 40 by the bracket 140 having a down-turned end 142 extending through an opening in the distributor. This bracket is secured to the header by the cap screws 144 and 146. The distributor 106 is similarly fastened at the other end of header 40.

For the purpose of promoting the mixing of the steam from the two headers 86 and 94, the distributors 104 and 106 are so constructed as to provide for the major flow of steam into the annular mixing chamber 108, at positions opposite to the header openings through which there is communication with the reheat tubes 32. For example, the distributor 104, as shown in Figs. 3 and 4, has a single row of outlet openings 150 along its lower side and adjacent the outlets to the reheat tubes 32, while at the opposite side of the distributor, there are three rows of openings 152 of similar or greater size. The distributor 106 is similarly provided with a single

row of openings 154 along its lower side and three rows of openings 156 along its upper side.

The header 40 at its ends is provided with flanges 160 and 162 for securing the flanged closures 164 and 166. Outwardly of the flanges 160 and 162 the header is provided with weld lips 168 and 170 adapted to fit similarly formed lips 172 and 174 on the flanged closures 166 and 164, respectively. When these lips are in contact, as shown in Fig. 6 of the drawings, they may be united by circumferential seal welds, while the main load is taken by bolts connecting the main flanges.

The header 40 is also provided with inspection or access openings as indicated at 176—178, each of these openings being closed by a seal weld 181 which unites a hemispherical cap (such as that shown at 180) and a tubular extension such as the extension 182.

Whereas the invention has been described with reference to the details of an installation in which a preferred embodiment of the invention is incorporated, it is to be understood that the invention is not limited to all of the described details. The invention is rather to be considered as of a scope commensurate with the scope of the subjoined claims which particularly point out the invention, in compliance with the federal statutes, and particularly section 4888 R. S.

What is claimed is:

1. In steam generator installations, a steam heater including a row of spaced tubes exposed to the heat of furnace gases, means forming an inlet chamber, conduits conducting steam to said chamber, the inlet ends of said tubes being connected to the chamber at spaced positions between said conduits, and oppositely tapered tubular distributors each conducting steam from one of the conduits toward the other and to the zones of the chamber covering the range of said positions, said distributors having lateral openings establishing communication with the inlet chamber.

2. In steam generator installation, a steam heater including a row of spaced tubes exposed to the heat of furnace gases, means forming an inlet chamber, conduits each of which conducts steam to said chamber from its separate fluid heating section, the inlet ends of said tubes being connected to the chamber at spaced positions between said conduits, and oppositely tapered tubular distributors each conducting steam from one of the conduits toward the other and to the zones of the chamber covering the range of said positions, said distributors being disposed within said chamber in endwise overlapping arrangement, and having lateral openings establishing communication with the inlet chamber.

3. In a steam generator, a furnace, steam generating tubes, a steam heater including spaced tubes exposed to the heat of the furnace gases, means forming an inlet chamber to which said spaced tubes are connected at a plurality of positions, tubular means conducting steam to said

chamber at spaced points between which said positions are located, and conversely tapering tubular distributors each conducting steam from one of said tubular means to the zones of said positions, said distributors being disposed alongside each other in endwise overlapping relationship within said chamber, and having lateral openings establishing communication with the inlet chamber.

4. In a fluid system, a fluid heater including a row of spaced tubes exposed to the heat of furnace gases, means forming an inlet chamber, conduits each of which conducts fluid from its separate fluid heating section to said chamber, the inlet ends of said tubes being connected to the chamber at spaced positions between said conduits, and oppositely tapered tubular distributors each conducting steam from one of the conduits toward the other and to the zones of the chamber covering the range of said positions, said distributors being arranged alongside each other in said chamber with each distributor terminating with its small end adjacent the larger and inlet end of the adjacent distributor, said distributors having lateral openings establishing communication with the inlet chambers.

5. In a steam generator, a furnace, a convection section, separate steam heating sections including separate groups of wall tubes exposed to the heat of the furnace gases at the opposite sides of a gas pass between the furnace and the convection section, a third steam heating section including a separate group of wall tubes exposed to the heat of the furnace gases, an inlet header for the third section, conduit means conducting steam from one of the first sections to one end of said header, conduit means conducting steam from another of the first sections to the other end of the header, the tubes of the third section being connected to said header at successive positions between said conduit means, and separate and oppositely tapered tubular distributors within said header and spaced inwardly of its interior wall, each distributor receiving the steam at its larger end from one of said conduit means and having lateral openings for distributing the steam along the header as far as a position adjacent the other conduit means.

6. In heat exchangers, means presenting a fluid chamber, a plurality of separate inlets through which said chamber receives fluid from different sources, a plurality of heat exchange tubes receiving fluid from said chamber at spaced positions therealong, and means for separately distributing throughout the chamber the fluid received through each inlet, said last named means including a plurality of oppositely tapered tubular elements which are arranged within the chamber in a complementary manner with the larger and inlet end of each adjacent the smaller end of the adjacent distributor, said distributors having lateral openings establishing communication with the inlet chambers.

PAUL R. LOUGHIN.
